CLAIM

The ornamental design for a sock, as shown and described.

DESCRIPTION

FIG. 1 is a perspective view showing a first embodiment of my new sock design in use;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a perspective view showing a second embodiment of my new sock design in use;

FIG. 9 is a top view thereof;

FIG. 10 is a bottom view thereof;

FIG. 11 is a right side view thereof;

FIG. 12 is a left side view thereof;

FIG. 13 is a front view thereof; and,

FIG. 14 is a rear view thereof.

The broken lines showing the foot depict environmental subject matter and form no part of the claimed design. The broken lines within the bounds of the sock depict features of the sock that form no part of the claimed design. The dot-dash broken line depicts a break line that forms no part of the claimed design. The cross-hatching lines in the drawings depict shading applied to the surfaces of the sock and do not reflect a particular surface ornamentation or material.
